Primary Examiner — Doris Clark(74) *Attorney, Agent, or Firm* — Dority & Manning, P.A.**CLAIM**

The ornamental design for a ribbed grab rail with cavity for light, as shown and described.

DESCRIPTION

FIG. 1 is a perspective view of the ribbed grab rail with cavity for light according to the present design; FIG. 2 is an alternate perspective view of the ribbed grab rail with cavity for light of FIG. 1; FIG. 3 is an end view of the ribbed grab rail with cavity for light of FIG. 1; FIG. 4 is a right or left side view of the ribbed grab rail with cavity for light of FIG. 1; FIG. 5 is a top view of the ribbed grab rail with cavity for light of FIG. 1; FIG. 6 is a bottom view of the ribbed grab rail with cavity for light of FIG. 1; and, FIG. 7 is a perspective view of the ribbed grab rail with cavity for light of FIG. 1, as installed using stanchions. The claimed design is shown broken in the center for ease of illustration.
